UNITED STATES PATENT OFFICE.

CHARLES W. BECK, OF NEW YORK, N. Y., ASSIGNOR, BY MESNE ASSIGNMENTS, TO ELECTROLITE GAS LAMP COMPANY, OF NEW YORK, N. Y.

ACETYLENE-GAS GENERATOR.

No. 820,468.

Specification of Letters Patent.

Patented May 15, 1906.

Application filed November 23, 1900. Serial No. 37,554.

To all whom it may concern:

Be it known that I, CHARLES W. BECK, a citizen of the United States, residing at New York, county of New York, and State of New York, have invented certain new and useful improvements in Acetylene-Generators, of which the following is a specification.

This invention relates to improvements in acetylene-generators, and refers more specifically to an improved carbid-feeding mechanism for feeding pulverulent or broken carbid.

The object of the invention is to provide a simple mechanism of the character referred to so constructed and arranged that the liability of its becoming clogged by reason of incrustation of carbid thereon or becoming jammed by lumps of carbid, so as to interfere with its free and regular operation, will be reduced to a minimum.

A further object of the invention is to so construct and arrange the parts as to protect the carbid passing through the feeding mechanism from damp air and steam until it has been delivered to the generating-chamber, thereby preventing the generation of gas during its transit through the feeding mechanism, and also obviating "after-generation" in case the feeding operation be interrupted.

To the above ends the invention consists in the matters hereinafter described, and more particularly pointed out in the appended claims, and the same will be readily understood from the following description, reference being had to the accompanying drawings, in which—

Figure 1 is an axial vertical sectional view of a generator and accompanying gasometer equipped with my invention. Fig. 2 is a fragmentary side elevation of the side of the gasometer adjacent to the generator, taken on line 2 2 of Fig. 1. Fig. 3 is a horizontal sectional view of the carbid-feeding mechanism proper, taken on line 3 3 of Fig. 1 and looking downwardly. Fig. 4 is a view in perspective of a modified form of feed-table.

Referring to said drawings, 1 designates as a whole a generator, which may be of any suitable or preferred construction, comprising an upper carbid-hopper 2 and a lower water-chamber 3, the hopper being arranged at some distance above the normal level of water within the reservoir, so as to provide

an intervening space, which constitutes the generator space or chamber 4 of the generator. The lower wall of the carbid-hopper extends laterally from the feed-opening and inclines outward and upward, it being adapted to direct the carbid toward the feed-opening and to sustain a greater part of the weight of the carbid.

Describing now more particularly the feeding mechanism constituting the present invention, the lower part of the carbid-hopper is provided with a discharge-opening 5, the lower margin of which, 6, is arranged horizontally, as indicated clearly in Fig. 1. At a short distance below the discharge-opening of the hopper is arranged a horizontally-disposed feed-table 7, suitably supported so as to be capable of being rotated intermittently and located at such distance below the end of the hopper that the carbid falling from the hopper upon said table will bank up so as to close the discharge-opening and not flow over the edges of the table while the latter remains stationary. The diameter of the feed-table and its relation to the discharge-opening of the hopper are such that while the table remains stationary the carbid will not flow over the edges of the latter; but, as above described, when the table is rotated the movement of the table relatively to the fixed end of the hopper will cause the carbid to gradually move radially outward and be discharged from the table.

In order to positively discharge the carbid from the table and at the same time insure its discharge at a particular point relatively to the stationary parts of the mechanism, I provide a wiper or deflector 8, preferably and as shown herein consisting of a blade arranged vertically with its lower edge extending from the periphery of the table obliquely inward a distance somewhat less than one-half of the diameter of the table and in a direction inclined forwardly and outwardly with reference to a radius of the feed-table and its direction of movement, so as to operate to brush the carbid resting near the periphery of the table outwardly and discharge it from the edge of the latter. Said wiper is conveniently and as shown herein supported by means of an arm 9, having one end attached to the interior of a housing 10, which surrounds the feed mechanism, and its oppo-

site end formed integrally with the outer end of the blade, as indicated clearly in the drawings.

In order that the damp vapors and steam caused by generation may not reach the carbid passing through the feed mechanism or that within the hopper through the feed-opening, I provide the housing 10, inclosing the feed mechanism, and provide said housing with a trap-door through which the carbid discharged from the feed-table is free to escape. Said housing preferably and as shown herein consists of a cylindric vertically-disposed inclosing wall 10, having its upper end suitably united with the conical lower end of the carbid-hopper concentric with the discharge-opening thereof and provided at its lower end at a point some distance below the feed-table with an inclined and conical end wall 11, through which is formed at its lower-most point and vertically beneath the wiper 8 a discharge-opening 12. 14 designates a horizontally-arranged trap-door which is arranged to control the discharge-opening 12. Said trap-door is pivotally mounted so as to be free to open downwardly, being conveniently provided with a supporting-arm 15, pivotally connected at a point between its ends, as at 16, with a suitable bracket or support 17 upon the side wall 10 of the housing and provided with a sliding weight 18, whereby the quantity of carbid necessary to open said door may be regulated.

As a preferred means of rotatably supporting the feed-table and imparting an intermittent motion thereto I provide a supporting-shaft 19, arranged to extend upwardly through the bottom wall 20 of the water-reservoir and engaged at its upper end with the lower side of the carbid-table at the center of the latter, such connection being conveniently formed by means of a socket 21, formed on the under side of the table, within which the upper end of the shaft extends and is secured by means of a cross-pin 22. In order to form a suitable seal around the shaft 19 and at the same time provide a suitable bearing within which the shaft is supported in its vertical position, I provide a sleeve 23, having its lower end threaded within the opening in the bottom wall 20 of the reservoir and within a reinforcing-casting 24, mounted upon the lower side of said wall concentric with said opening and arranged to extend thence upwardly to a point well above the normal level of the liquid within said reservoir. Upon the shaft 19 is mounted a bell 25, which is arranged to telescope over the sleeve 23, the lower end of the bell terminating above but adjacent to the bottom of the reservoir.

In order to afford access to the feed mechanism, the upper member of the generator or hopper is made to separate from the lower member on a line extending through the

housing 10, as indicated at 26, the parts being conveniently united by means of screws or bolts 26', as shown clearly in the drawings.

Any suitable or preferred means may be employed for imparting to the feed-table an intermittent rotary movement—as, for example, in the case of comparatively large generators, from which the gas is conveyed to a suitable gasometer or reservoir, the feed-table may be rotated from time to time manually by means of any suitable mechanism. Preferably and as shown herein, however, means are provided whereby said table is rotated intermittently and automatically, the frequency of movement being determined by the consumption of gas generated. To this end the lower end of the shaft 19 is provided with a bevel-gear 27, with which intermeshes a second bevel-gear 28, mounted upon a shaft 29, arranged to extend outwardly through a suitable bearing 30 and through the side wall of the generator and engaging a second bearing 31, mounted upon the exterior of a gasometer, (designated as a whole 32.) Said gasometer 32 is of a usual type, comprising a lower receptacle or member 33 and an upper member or bell 34, telescoping within said lower member and having its lower end immersed in liquid, as usual, a gas-pipe 35 affording communication between the upper part of the generating-chamber of the generator and the interior of the bell, as indicated clearly in the drawings. Upon the shaft 29, adjacent to the gasometer, is mounted a sprocket-wheel 36, and at a point some distance above said sprocket is mounted a second sprocket 37. 38 designates a sprocket-belt arranged upon said sprockets, and 39 designates a ratchet-plunger mounted to reciprocate vertically in suitable guides or supports 40 41, adjacent to and parallel with one side of said belt, as best indicated in Fig. 2. Upon said plunger is mounted a pawl or hook 42, which is adapted to engage positively with the links of the belt when the plunger is thrust downwardly, but to slide past the links ratchet fashion when the plunger rises, so as to impart a rotation to said belt in one direction only or upon the downward movement of said plunger. The upper surface of the pawl 42 at the outer end thereof is beveled downwardly to permit the pawl to slide over the chain-links as the gasometer is raised, while its under surface is horizontal, so that when the gasometer descends the end of the pawl will engage one of the chain-links and carry the engaged part of the chain downward.

43 designates a bar mounted rigidly upon the bell of the gasometer and having its lower end arranged to extend in alinement with the upper end of the plunger 39 and so located with reference to the bell that when the latter is approaching the lower limit of its movement said bar will engage the plunger and force the latter downwardly, thereby

rotating the shaft 29 and, through the connections hereinbefore described, rotating the feed-table. The plunger 39 is returned and normally held at its uppermost limit by means of a coiled expansion-spring 44, interposed between the lower support 41 and the pawl 42.

The hopper 2 is provided with a suitable inlet-aperture 45, closed by a screw-block 46, as usual, and likewise the reservoir or generator body 3 is provided with a supply-pipe 47 and a discharge-pipe 48, each controlled by a suitable stop-cock, as 49 and 50, respectively. In the preferred construction shown herein the inlet-pipe 47 is arranged to communicate with the lower part of the reservoir and is made of relatively large diameter and extended vertically upward to a point well above the highest level of liquid within the reservoir, the object of this construction being to enable the operator to tell by inspection about how much liquid is contained in the reservoir. As a protection against overfilling the supply-pipe is provided with an overflow-aperture 51, located at a point coincident with the highest level to which the reservoir should be filled. The bottom of the reservoir 20 is inclined and the outlet-pipe 48 located at the lower side thereof, so that the residue 30 and sludge may be readily removed, and in this connection it is to be noted that should the sludge have a tendency to accumulate on the floor of the reservoir it may be readily flushed off by leaving both inlet and outlet 35 pipes open and running water through the reservoir, it being noted that the inlet-pipe discharges near the upper side of the inclined bottom, so that the course of the liquid would be directly across the bottom of the 40 reservoir. The gasometer is provided with the usual outlet gas-pipe 52, conveniently arranged to extend up through the bottom wall, and terminates at its inner end at a point well above the level of the sealing liquid 45 therein.

The operation of the apparatus constructed as thus described is probably entirely obvious, but may be briefly recapitulated as follows: The hopper and reservoir having 50 been suitably charged with carbid and water, respectively, the apparatus may be brought into operation initially by rotating the feed-table in any suitable manner—as, for example, manually—until a first supply of gas is 55 formed. As the feed-table rotates carbid will be discharged therefrom by the wiper and will fall upon the trap-door 14, accumulating thereon until its weight overcomes the counterbalance-weight, whereupon the carbid will be dumped and the trap-door again closed. The carbid falling within the water 60 generates a supply of gas, which, filling the generating-chamber, passes through the pipe 35 to the bell of the gasometer and raises the latter. After the first supply of gas has been

formed the generation becomes automatic. As the gas is consumed and the bell falls the lower end of the bar 43 engages the ratchet-plunger and operates that mechanism in the manner hereinbefore described, thus repeating the operation of feeding carbid to the liquid, it being obvious that as soon as a second supply of carbid is dumped the fresh supply of gas generated will fill and lift the bell and permit the ratchet-plunger to rise in readiness to repeat the feeding operation.

It will of course be understood that there are numerous well-known ways in which the feed mechanism proper may be operated, either automatically or intermittently, at will. In Fig. 4 I have shown an improved form of feed-table more particularly adapted for use in a feed mechanism constructed generally like that described, but in which the wiper is omitted and in which the lower end 85 wall of the feed-mechanism housing is either omitted or provided with a suitable opening to permit the passage of the carbid flowing over the periphery of the table throughout its entire circumference. Said modification 90 consists in providing the feed-table 53 with a conical upper side portion 54, provided with spirally-arranged ribs 55, which are adapted to act upon the pulverulent carbid to force the latter gradually radially outward, so as 95 to discharge it over the periphery of the table at all points thereof. It will be obvious that the weight of the accumulated carbid resting upon the table and held from rotation so far as its main body is concerned by reason of its 100 continuity with the body of carbid within the hopper will be acted upon by the spirally-flanged upper surface of the table screw fashion, and the carbid thus discharged in an approximately positive manner. This construction has certain advantages over the previously-described construction, among which may be mentioned that by reason of the omission of the wiper or deflecting-plate 105 there is less liability of the feed mechanism becoming clogged by the presence of a lump or several lumps forming a wedge of carbid. A feed-table of this type may obviously be employed in conjunction with a generator like that herein described, it being obvious 110 that the inclined lower wall 11 of the housing which surrounds the feed-table will act to direct the carbid discharged from the periphery of the feed-table to the discharge-aperture 115 12 thereof and that the operation will therefore be substantially the same as that of the first-described construction.

While I have herein shown and described what I deem to be a preferred embodiment of my invention, yet it will be obvious that the 125 details thereof may be modified to some extent without departing from the invention, and I do not, therefore, wish to be limited to the precise details shown except as they are made the subject of specific claims.

I claim as my invention—

1. A carbid-feeding mechanism for feeding loose carbid, comprising a suitable hopper or source of carbid-supply formed with a discharge-opening, a horizontal feed-table located a short distance below said discharge-opening, a stationary wiper mounted to brush the carbid from the table as the latter is rotated relatively thereto, a housing 5 closing said feed mechanism and provided at a point vertically below the point of discharge of the feed-table with a trap-door, and means for rotating said feed-table intermittently, substantially as described. 10
2. A carbid-feeding mechanism for feeding loose carbid comprising a carbid-hopper provided with a conical lower end portion terminating in a circular horizontally-arranged feed-aperture, a circular horizontally-disposed feed-table supported a short distance below the lower end of said aperture, a stationary wiper supported above said table so as to brush the carbid therefrom as the latter is rotated, a housing mounted upon the 15 lower side of the hopper inclosing the feed mechanism and provided in its lower side at a point vertically beneath the discharge-point of the feed-table with an opening and a pivoted trap-door closing said opening, an adjustable weight arranged to regulate the 20 opening of said door, and means for rotating said feed-table intermittently, substantially as described. 25
3. In an acetylene-generator, the combination of an upper hopper provided with a feed-opening, a horizontally-disposed feed-table mounted below said feed-opening and co-operating with the latter to control the flow of carbid from the hopper, a liquid-reservoir 30 below said feed mechanism, and means for supporting and operating said feed-table; comprising a shaft arranged to rise vertically through the bottom wall of said liquid-reservoir and engaging and supporting said table at its upper end, and a liquid seal surrounding 35 said shaft without changing its angular relation or position with respect to the wall of the feed-opening of the carbid-holder, substantially as described. 40
4. In an acetylene-generator, the combination of a suitable hopper or source of carbid-supply formed with a discharge-opening, a horizontal feed-table located at a short distance below said discharge-opening, a wiper mounted above said feed-table in position to brush the carbid therefrom as the table is rotated, a yieldably-mounted support upon which the carbid is discharged from the feed-table and from which it is dumped in accumulated quantities, and mechanism operated 45 automatically by the volume of gas generated, operating to rotate said feed-table intermittently, substantially as described. 50
5. In an acetylene-generator, the combination of a suitable hopper or source of carbid- 55 supply formed with a discharge-opening, a horizontal rotary feed-table located at a short distance below said discharge-opening, a casing below said feed-table having inclined side walls adapted to direct the carbid discharged from the feed-opening to the lowest part of said casing, a discharge-opening being formed through said casing at its lowest point, and a downwardly-opening, yieldingly-mounted, trap-door controlling said discharge-opening and from which the carbid is dumped in accumulated quantities, substantially as described. 60
6. In an acetylene-generator, the combination of a suitable hopper or source of carbid-supply formed with a discharge-opening, a horizontal rotary feed-table located at a short distance below said discharge-opening, a casing below said feed-table having inclined side walls adapted to direct the carbid discharged from the feed-opening to the lowest part of said casing, a discharge-opening being formed through said casing at its lowest point, and a downwardly-opening, pivotally-mounted, trap-door provided with a counterbalance-arm, and a weight adjustably mounted upon said counterbalance-arm, as and for the purpose set forth. 65
7. In combination with an acetylene-generator, provided with an intermittently-operated feed mechanism, means for actuating said feed mechanism controlled by the consumption of gas generated, comprising a gasometer provided with a rising and falling bell, an operating-arm carried by said bell, a spring-returned plunger adapted to be engaged by said operating-arm during the descent of the bell, a sprocket-belt mounted adjacent to said spring-returned plunger, having one of its laps parallel with the path of movement of the plunger, a pawl-hook upon said plunger adapted to positively engage and operate the belt during the descent of the plunger and to slide past the links of the belt, ratchet fashion, during its return movement, and a driving-shaft actuated by said sprocket-belt and operatively connected with the feed mechanism, substantially as described. 70
8. A carbid-feed mechanism for feeding lump-carbid comprising a carbid-hopper provided with a downward-inclined lower portion adapted to direct the carbid toward a feed-aperture and to sustain the greater part of the weight of the carbid, a horizontal feed-table supported a short distance below the feed-aperture, a wiper supported above said table so as to brush the carbid from the table as the latter is rotated, a gas-tight tank inclosing the table and the wiper and adapted to contain the liquid-supply, and means actuated by variations in gas-pressure to rotate said table. 75
9. An acetylene-generator comprising a liquid-holder, a carbid-holder having a feed- 80

- opening, a two-part feed mechanism located below the feed-opening so that a mass of carbid will extend from the feed mechanism to the feed-opening, the parts of the feed mechanism being a fixed distance from the feed-opening, means actuated by variations in gas-pressure for operating the feed mechanism without varying the distance between the members of the feed mechanism and the feed-opening.
10. In an acetylene-gas generator, the combination of a liquid-holder, a carbid-holder above the liquid-holder and provided with a feed-opening, and a two-part feed mechanism consisting of a support below the feed-opening and adapted to sustain a mass of carbid below the wall of the feed-opening, a stationary device between the support and the feed-opening, and means operated by variations in the gas-pressure for actuating the feed mechanism without changing the angular position of said support with respect to the wall of the feed-opening.
11. In an acetylene-gas generator, the combination of a liquid-holder, a carbid-holder above the liquid-holder and provided with a feed-opening, and a two-part feed mechanism consisting of a table below the feed-opening and adapted to sustain a mass of carbid below the wall of the feed-opening, a device between the table and the feed-opening, and means operated by variations in the gas-pressure for actuating one of the parts of the feed device to cause the carbid to be moved from the support.
12. In an acetylene-generator, the combination of a liquid-holder, a carbid-holder above the liquid-holder and provided with a feed-opening, a rotatable feed-table below said feed-opening, a non-rotary feed device between the feed-table and the feed-opening, and means actuated by the variations in gas-pressure for rotating the feed-table.
13. In an acetylene-generator the combination, of a suitable hopper or source of carbid-supply provided with a suitable discharge, a horizontal feed-table located at a short distance below said discharge, a yieldingly-mounted support below the table and adapted to receive the carbid therefrom and which is adapted to discharge the carbid in quantities into the generating-chamber, and a mechanism operated automatically by gas-pressure to rotate said feed-table intermittently, and a wiper arranged between the feed-table and the carbid-discharge and adapted to engage the carbid and cause it to fall from the table.
14. In an acetylene-generator the combination, of a hopper formed with a contracted lower end and provided with a discharge-opening at the bottom of said contracted portion, whereby the weight of the mass of carbid will not be supported by the feed-table, a horizontal feed-table located a suitable distance be-
- low said discharge, said feed-table being larger in diameter than the discharge-opening, whereby the carbid will not flow while the table is stationary but will be discharged over the edge of the table when the same is rotated, and a mechanism operated by variations in gas-pressure to intermittently rotate said table without altering its distance from the discharge-opening, whereby the carbid-passage will be at all times open and unobstructed and of the same dimensions.
15. In an acetylene-generator the combination, of a hopper provided with a discharge-opening at its bottom, a horizontal feed-table located a suitable distance below said discharge, said feed-table being larger in diameter than the discharge-opening whereby the carbid will not flow when the table is stationary, but will be discharged over the edges of the table when the same is rotated, and a mechanism operated by variations in gas-pressure to intermittently rotate said table without causing it to approach the discharge-opening, whereby the path of the carbid from the hopper to the generating-chamber will be at all times open and unobstructed and of the same dimensions.
16. An acetylene-gas generator comprising a gas-tight liquid-holder and generating-tank, a carbid-holder above the liquid-holder and provided with a feed-opening in its bottom adapted to discharge carbid into the liquid-holder, a two-part feed mechanism consisting of a support directly below the feed-opening and adapted to sustain a mass of carbid below the wall of the feed-opening, and a feed device between the support and the feed-opening, a gas-holder, and means operated by variations in the volume of gas in the gas-holder for operating one of the parts of the feed device to cause carbid to drop from the support into the liquid-holder to generate gas.
17. An acetylene-generator comprising a gas-holder, a gas-tight liquid-holder, a carbid-holder above the liquid-holder and provided with a feed-opening, said carbid-holder being constructed to discharge the carbid in a continuous stream, means below the discharge-opening for sustaining a loose mass of carbid below and outside the carbid-holder but in contact with the carbid in the carbid-holder, and means for intermittently discharging a portion of said loose mass into the liquid-holder, said means being operated automatically by variations in volume of gas in the gas-holder, whereby the continuity of the stream of carbid from the carbid-holder is maintained.
18. An acetylene-generator comprising a gas-holder, a gas-tight liquid-holder, a carbid-holder above the liquid-holder and provided with a feed-opening, said carbid-holder being constructed to discharge the carbid in a continuous stream, a table below the discharge-opening for sustaining a loose mass of carbid

- below and outside the carbid-holder but in contact with the carbid in the carbid-holder, means for discharging a portion of said loose mass over the edge of the table and into the liquid-holder, and means operated automatically by variations in the volume of gas in the gas-holder for rotating said table, substantially as and for the purpose set forth.
19. An acetylene-gas generator comprising a gas-holder, a gas-tight liquid-holder, a carbid-holder above the liquid-holder and provided with a feed-opening in its bottom and adapted to automatically discharge the carbid, feed mechanism consisting of two members, one member being a table supported be-
- 5
- 10
- 15

low the feed-opening at a point where it will sustain a loose mass of carbid below the feed-opening and the other member being a feed device located between the table and the feed-opening and adapted to engage into the loose mass of carbid, and means for moving one of the members whereby the carbid will be moved off the edge of the table, said means being automatically operated by the changes in volume of the gas in the gas-holder.
